Patented May 4, 1920.

Inventor,

Moses F. Fybush;

By Raymond J. Hulka,
Attorney.

UNITED STATES PATENT OFFICE.

MOSES F. FYBUSH, OF LOS ANGELES, CALIFORNIA.

DESIGN FOR A CABINET FOR A TALKING-MACHINE.

55,033.

Specification for Design.

Patented May 4, 1920.

Application filed August 8, 1919. Serial No. 316,268. Term of patent 14 years.

To all whom it may concern:

Be it known that I, MOSES F. FYBUSH, a citizen of the United States, residing at Los Angeles, in the county of Los Angeles and State of California, have invented a new, original, and ornamental Design for a Cabinet for Talking-Machines, of which the following is a specification, reference being had to the accompanying drawing, forming part hereof, and of which—

The figure is a perspective view of a cabinet for talking machines which embodies the invention.

I claim:

The ornamental design for a cabinet for a talking machine, as shown.

MOSES F. FYBUSH.

Witnesses:

RAYMOND I. BLAKESLEE,
EDNA TURNER.
